Harold J. Wolfe and Dale O. Crawford,
Seattle, Wash.

Application March 25, 1950, Serial No. 8,782

Term of patent 14 years

(Cl. D16—2)

To all whom it may concern:

Be it known that we, Harold J. Wolfe and Dale O. Crawford, are citizens of the United States, residing at Seattle, in the county of King and State of Washington, have invented a new, original, and ornamental Design for a Dehumidifier, of which the following is a specification, reference being had to the accompanying drawing, forming part thereof:

Fig. 1 is a top plan view of a dehumidifier embodying our new design.

Fig. 2 is an elevational view thereof.

The dehumidifier embodying our invention is round in shape and has the same appearance from all angles.

We claim:

The ornamental design for a dehumidifier, as shown and described.

HAROLD J. WOLFE.
DALE O. CRAWFORD.
